Benjamin G. Fox Inventor.

Inventor.

By John W. Nichols

Attorney.

UNITED STATES PATENT OFFICE.

BENJAMIN G. FOX, OF PRICETOWN, PENNSYLVANIA.

HORSESHOE.

SPECIFICATION forming part of Letters Patent No. 567,740, dated September 15, 1896.

Application filed April 1, 1896. Serial No. 585,693. (No model.)

To all whom it may concern:

Be it known that I, BENJAMIN G. FOX, a citizen of the United States, residing at Price-
town, county of Berks, State of Pennsylva-
nia, have invented certain Improvements in
5 Horseshoes, of which the following is a speci-
fication.

My invention relates to certain improve-
ments in horseshoes and calks therefor, where-
10 by the latter may be more readily secured
and replaced and at the same time more ef-
fective in service than heretofore.

The invention is fully described in con-
nection with the accompanying drawings.

15 Figure 1 is a sectional view taken on the
line $x x$ of Fig. 2. Fig. 2 is a bottom plan
of the shoe, showing one end of the toe-calk
broken away and the heel-calk entirely re-
20 moved. Fig. 3 is a cross-sectional view
through the heel-calk mortise. Fig. 4 is a
separate view of the toe-calk.

25 A represents the toe, and A' A' the heels,
of a horseshoe having my improvements ap-
plied thereto. The toe A is formed with a
dovetailed mortise a' in its forward edge, and
30 the thickness of the shoe to the rear of this
mortise is increased by adding metal at the
bottom, as indicated at a, the object of this
increased thickness at the point being to pro-
35 vide for the proper seating and securing of
the toe-calk B without weakening the shoe.

40 The calk B is provided with a tenon or
shank portion b, fitting the mortise a' and
having its upper end b' extending above the
shoe, so as to form a stop for the hoof to
45 abut against. The portion of the calk which
extends below the shoe tapers off to a wear-
ing edge b³, the sides of which bend inward,
as shown at b⁴, thus forming a crescent or
50 shallow-U shaped bearing calculated to pre-
vent side slippage. The shoulder b², at the
intersection with the shank or tenon of the
calk, seats against the bottom surface of the
55 shoe just beyond the thickened-up portion a
and is drawn up tight against said surface
in the act of driving the securing wedge or
key C. This key passes horizontally through
60 perforations in the shank of the calk and in
the thickened-up portion of the shoe, and
when firmly driven is secured by clenching
at c.

The heel-calks D are wedge-shaped longi-
tudinally in opposite directions, as shown in

Figs. 1 and 3, thus forming a wearing edge
d and a shank d', which is adapted to en-
gage the dovetailed mortise a² in the shoe, so
as to effectually prevent movement of the
calk in either direction when it has been in-
5 inserted in the mortise and forced to one end
thereof by means of a key E, the upper end
of which is clenched over to positively retain
it. The driving in of the calk beyond its
proper position is prevented not only by the
10 increasing thickness of the shank, as indi-
cated in Fig. 3, but also by a shoulder d²,
Fig. 1, while its withdrawal is prevented by
the increasing width toward the top of the
shank engaging the correspondingly-elon-
15 gated mortise so long as the key E is in place.

When worn, both heel and toe calks may
20 be readily removed by chipping off the
clenched-over ends of the keys E and C, re-
spectively, and driving them out, thus re-
leasing the calks.

I am aware that toe and heel calks of dif-
25 ferent shapes have heretofore been secured
to horseshoes by differently-formed tenon-
and-mortise connections, and I do not broadly
claim such constructions as of my invention.

What I claim is—

30 1. The combination with a horseshoe hav-
ing a vertical dovetailed mortise in the edge
thereof and increased thickness of cross-sec-
tion at said mortise, of a toe-calk having a
dovetailed tenon or shank fitting the mortise 35
and a shoulder seated against the under side
of the shoe, and a key passing horizontally
through the calk-shank and the thickened
portion of the shoe to firmly unite the same
45 substantially as set forth.

40 2. The combination with a horseshoe hav-
ing a dovetailed mortise in the edge thereof
and increased thickness of cross-section at
said mortise, of a toe-calk having a tenon or
shank fitting the mortise and a crescent or 45
50 U shaped wearing extension seated against
the lower face of the shoe and partially inclos-
ing said increased shoe-section, with means
for removably securing the calk to the shoe,
55 substantially as set forth.

60 In testimony whereof I affix my signature
in presence of two witnesses.

BENJAMIN G. FOX.
